CLAIM

I claim the ornamental design for a food product container, substantially as shown and described.

DESCRIPTION

FIG. 1 is an isometric view of a food product container of the present invention;

FIG. 2 is a side elevation view thereof;

FIG. 3 is a top plan view thereof; and,

FIG. 4 is a bottom plan view thereof.

The thin broken line portion of the drawings in FIGS. 1-4 is included to show unclaimed subject matter only and forms no part of the claimed design.

The claimed subject matter extends to heavy broken line portion of the drawings in FIGS. 1-4, which defines the boundary of the claim only and forms no part of the claimed design.
